UNITED STATES PATENT OFFICE.

ALBERT LARKIN, OF ALMOND, NEW YORK.

IMPROVEMENT IN IRONING-TABLES.

Specification forming part of Letters Patent No. 159,688, dated February 9, 1875; application filed July 10, 1874.

To all whom it may concern:

Be it known that I, ALBERT LARKIN, of Almond, in the county of Allegany and State of New York, have invented certain new and useful Improvements in Combined Ironing-Table, Clothes-Basket, Clothes-Rack, &c.; and I do hereby declare that the following is a full, clear, and exact description thereof, reference being had to the accompanying drawings, and to the letters of reference marked thereon, which form part of this specification.

The nature of my invention consists in the combination of certain bars and elements, whereby a folding structure is obtained which may be used as an ironing-table with clothes-rack and clothes-basket, and for various other purposes, as will be hereinafter more fully set forth.

In order to enable others skilled in the art to which my invention appertains to make and use the same, I will now proceed to describe its construction and operation, referring to the annexed drawings, in which—

Figure 1 is a front view of my folding-structure when used as an ironing-table, with clothes-rack and clothes-basket. Fig. 2 is a transverse vertical section of the same through the line *x x*, Fig. 1. Figs. 3, 4, 5, and 6 show the structure in various other positions; and Fig. 7 is a section through one of the joints.

A A represent the front legs, and B B the rear legs. The two front legs, A A, are connected by the front C, having pins *a a* at its upper and lower corners at each end passing through the legs. The rear legs B B are connected in a similar manner by a back, D, having pins *b b* passing through said legs. The front C and back D are slotted, or otherwise made open. The bottom pins of the front and back on each side pass through a cross-bar, E, thereby connecting the front and rear legs. The cross-bars E E have the bottom G secured to them, as shown. On each of the top pins of the front C is pivoted a bar, H, the other end of which is slotted longitudinally for a suitable distance, and passed over the pin *b*

of the back D, as shown. To the upper end of each front leg, A, is pivoted an arm, I, the other end of which is cut with a square notch, *e*, on the under side, to fit over one of the square bars J of the clothes-rack system, hereinafter described. The arms I, being held horizontally, form supports for an ironing-table, K, as shown in Fig. 2, the front C, back D, and bottom G forming a clothes-basket. The rear legs B are extended upward for a suitable distance, and to each is connected a system of arms, L L, connected by transverse bars J J. The bars J J are made square, and provided with round tenons *d* passing through the arms L.

The arms L and bars J may be arranged in any suitable manner to form a folding and extension clothes-rack. One of the arms L on each side forms an additional leg, as shown in the drawings.

This combination of elements may be used for various other purposes—for instance, as a writing-desk, as shown in Fig. 3, or as a settee, as shown in Fig. 4. In Fig. 5 I have shown it as a crib, and in Fig. 6 as clothes-bars only. When used for these purposes the table K will, of course, have to be removed.

It can be extended or unfolded in a variety of ways, and when not in use it may be folded up in a very small compass and put away.

Having thus fully described my invention, what I claim as new, and desire to secure by Letters Patent, is—

The combination of the legs A B, front C, back D, cross-bars E, bottom G, arms H I, and the system of arms L, and bars J, and with or without the table K to form the various articles, substantially as shown and described.

In testimony that I claim the foregoing as my own, I affix my signature in presence of two witnesses.

ALBERT LARKIN.

Witnesses:

P. L. GREEN,
C. A. STRAIGHT.
